WIRE STRAIGHTENER

Charles D. Johnson, Worcester, Mass., assignor to
Johnson Steel & Wire Company, Inc., Worcester,
Mass., a corporation of Massachusetts

Application April 4, 1934, Serial No. 718,969

1 Claim. (Cl. 140—137)

This invention relates to wire straighteners and particularly to wire straighteners of that type which comprise two straightener elements having a tandem arrangement and through both of which the wire to be straightened passes. Wire straighteners of this type are frequently referred to as "two-way" straighteners. These two-way straighteners are sometimes in the nature of rotary straighteners and sometimes in the nature 10 of pin or roller straighteners. In the straighteners of the latter class the straightening of the wire is done by passing the wire between two rows of pins or rolls which are so arranged that as the wire passes between said rows it is flexed first in one direction and then in the other.

In a "two-way" straightener of the pin or roll type the pins or rolls of one straightener element are arranged at right angles to those of the other so that the flexing of the wire will take 20 place in two planes at substantially right angles to each other.

In the case of a rotary straightener it is usual to provide for rotating the two straightener elements in opposite directions.

25 In both types of straighteners it is customary to provide means by which the amount which the wire is flexed in passing through the straightener may be adjusted, and in the case of a pin or roll straightener this adjustment is provided for 30 by a construction which permits the two rows of pins of either element to be adjusted toward or from each other.

35 In the operation of a two-way straightener the wire is passed through the two straightener elements successively and then is wound on a driven receiving drum, the friction of the turns of wire about the drum being sufficient to draw the wire through the two straightening elements. The tension or pulling strain on the wire as it is wound 40 on the receiving drum is sufficient to overcome the frictional resistance of the wire in passing through both of the straightening elements and the result is that the wire which is delivered to the second straightening element is under a 45 sufficient tension or pulling strain not only to draw it through the first of the straightening elements but also to withdraw it from the reel or swift from which the wire is supplied.

50 With this arrangement the length of wire which is passing through the second straightener element is subjected at one end to a back drag or retarding pull equal to the pulling strain necessary to pull the wire through the first straightener element and at the other end it is subjected to a pulling strain sufficient to pull the

wire through both of the straightener elements. Any adjustment which is made in the first straightener element by which the pulling strain necessary to draw the wire through said element is increased or decreased will, therefore, affect the back drag or retarding pull on the wire as it is passing through the second straightener element and will thereby effect the operation of said second straightener element.

5 Because of the fact that the effect produced 10 on the wire by each straightener element is dependent on the adjustment of the other straightener element it is very difficult to make any proper adjustments to overcome any tendency 15 for the wire to spiral. The method now commonly used is a sort of "cut-and-try" method, the operator making an adjustment of one of the straightener elements and then observing the wire to see if such adjustment has corrected the fault and if it has not then he makes some other adjustment, either of one or both of the straightener elements in a further attempt to correct 20 the fault, these experimental adjustments being repeated till the desired results are approximately 25 achieved.

In order to overcome this difficulty and to produce a straightener which can be readily adjusted to produce a straight wire I propose to provide a wire straightener which is constructed 30 so that the wire will be delivered to each straightener element substantially free from tension, so that the only pulling strain to which the wire is subjected as it is passing through each straightener element is that necessary to draw it through 35 said element. I provide for this by installing a capstan or its equivalent between the source of supply and the first wire straightener element and which operates to draw the wire from the source of supply and deliver it to the first straightener element substantially free from tension, and by installing a second capstan between the straightener elements and which serves to draw the wire through the first straightener element 40 and deliver it substantially free from all tension to the second straightener element. 45 With this arrangement the operation of each straightener element is entirely unaffected by any adjustment in the other straightener element and it is possible for the operator to quickly make such adjustments in the straightener elements 50 as necessary to produce a straight wire and to prevent the wire from having a spiraling tendency after it passes through the straighteners.

In order to give an understanding of the invention I have illustrated in the drawing a

selected embodiment thereof which will now be described after which the novel features will be pointed out in the appended claim.

Fig. 1 is a side view of a wire straightener embodying my invention:

Fig. 2 is a top plan view thereof;

In the drawing 1 indicates the wire to be straightened and this is shown as being taken from a coil or bundle 2 of wire carried by the swift 3.

While the invention is applicable to wire straighteners of either the rotary type, or the pin or roll type, I have chosen to illustrate it as it might be embodied in a wire straightener of the roll or pin type.

4 and 5 indicate two straightener elements each of the roll type and both of which are mounted on a suitable supporting frame 22. The straightener element 4 is of the type having two rows of rolls or pins 6 between which the wire 1 passes, said rows having such a relative position that as the wire passes between them it is flexed first in one direction and then in the opposite. The straightener element 5 is similar in construction except that its rolls 6 are mounted on axes situated at right angles to the axes of the rolls of the first straightener. In the first straightener 4 the rolls 6 rotate about horizontal axes and in the second straightener 5 the rolls rotate about vertical axes.

Each straightener is made adjustable in some suitable or usual way as by means of the adjusting screws 7, so that the two rows of rolls or pins of each straightener element can be adjusted toward or from each other thereby varying the amount or degree of flexing to which the wire is subjected as it passes through the straightener element.

8 indicates a usual wire-receiving drum on which the wire is wound as it is drawn through the straightener, said drum being mounted on and rotated by a driven shaft 9 as usual in wire straighteners.

As stated above the present invention provides a novel construction by which the wire is delivered to each straightener element 4 or 5 substantially free from tension. One way of accomplishing this is to provide a capstan between the straightener element 4 and the swift 3 and by which the wire is drawn off from the swift and delivered to the straightener element 4, and to provide another capstan between the straightener elements which serve to pull the wire through the straightener element 4 and deliver it to the straightener element 5.

The first-mentioned capstan comprises two drums or pulleys 10 and 11 around which the wire 1 passes several times in its passage from the swift 3 to the straightener element 4.

The drum 10 is a driven drum and is mounted on a shaft 21 supported in the frame 22. The drum 11 is an idler also supported on said frame. The wire is wound around these drums a sufficient number of times to provide the necessary friction to draw the wire from the swift.

The other capstan comprises the two drums 12 and 13 around which the wire passes several

times in its journey from the first straightener element 4 to the second straightener element 5. The drum 12 is mounted on a driven shaft 17 which is journaled in the frame 22 and the drum 13 is also rotatively mounted in said frame but is in the nature of an idler.

The wire coming from the straightener element 4 passes around the drum 12, thence around the drum 13, thence around the drum 12 again and so on a sufficient number of turns and then the wire is delivered to the straightener element 5. The drum 12 is power driven and furnishes the power for drawing the wire through the straightener element 4.

Any suitable way of driving the power-driven drums 10 and 12 may be employed without departing from the invention. As herein shown the power-driven shaft 9 for the receiving drum 8 is provided with a pulley 14 which is connected by a belt 15 to a pulley 16 on the shaft 17 of the drum 12. This shaft 17 has another pulley 18 thereon which is connected by a belt 19 to a pulley 20 on the shaft 21 of the drum 10. Both the driven drums 10 and 12 thus derive their rotation from the power-driven shaft 9.

It will be understood that the pulleys 14, 16, 18 and 20 will be of the proper size to give the power-driven drums 10 and 12 the proper surface speed to draw the wire from the swift and through the wire straightener element 4 and to deliver the wire to the two straightener elements substantially free from tension and without the accumulation of any slack in the wire.

With this arrangement the operation of each straightener element will be unaffected by any adjustment in the other straightener element and this arrangement facilitates the securing of the correct adjustment of the straightener elements to produce a straight wire.

While I have illustrated the invention as applied to a two-way wire straightener of the pin or roll type yet I desire to state that the invention is equally applicable to a straightener of the rotary type and in applying the invention to a rotary straightener a capstan or its equivalent will be placed between the two rotary elements of the rotary straightener and will operate to draw the wire through the first rotary element and deliver it to the second element. If desired, a capstan or its equivalent also may be placed between the source of wire supply and the first rotary element.

I claim:

A wire straightener comprising a capstan for drawing wire from a source of supply, a straightener to which the wire is fed from said capstan and which gives the wire a series of alternate opposite bends, a second capstan for drawing the wire through said straightener, a second straightener to which the wire is fed from the second capstan and which gives said wire a series of alternate bends in a plane at right angles to the plane in which the bends are made by the first-named straightener and a power driven wire-receiving drum on which the wire is wound as it is drawn through the second straightener.

CHAS. D. JOHNSON.
